UNITED STATES PATENT OFFICE.

ANTOINETTE ZINGALL, OF NEW YORK, N. Y.

SQUARE FOR DESIGNING GARMENT PATTERNS.

Application filed October 29, 1925. Serial No. 65,551.

This invention relates to squares and has for an object to provide an improved construction especially adapted for designing garments, the structure being such that from the square guiding lines may be drawn quickly and accurately for indicating the position of lines of a desired pattern.

Another object of the invention is to provide a square for use in designing patterns wherein a set of indications are provided to use in connection with designing the body of a tight fitting waist and other indications are provided for guiding a person in designing the sleeve of the waist.

A still further object, more specifically, is to provide a square capable of being disassembled, the structure being so formed that when assembled it will present usual measurements and in addition, arbitrary signs for both the body and sleeves, and signs indicating the position of the construction lines on a pattern.

In the accompanying drawings—

Figure 1 is a plan view of a square, disclosing an embodiment of the invention, a pattern being shown in connection therewith for better illustrating the construction and use of the square.

Figure 2 is a fragmentary sectional view through Figure 1 on line 2—2.

Figure 3 is an enlarged fragmentary sectional view of one corner of the square shown in Figure 1 illustrating how the parts may be assembled and disassembled.

Figure 4 is a view similar to Figure 1 but showing the sleeve pattern in connection with the square.

Referring to the accompanying drawings by numerals, 1 indicates a sheet of paper on which the pattern 2 is adapted to be drawn while 3 indicates the entire square. The square 3 is formed from two rulers, namely, rulers 4 and 5, said rulers being connected together at the corners by a suitable connection shown particularly in Figure 3. From this Figure it will be observed that there is a corner piece 6 having a socket 7 in which the tongue 8 connected with the ruler 4 is inserted. The tongue 8 is formed with a slit 9 whereby a resilient tongue 10 is provided. This permits the tongue 8 to be readily inserted or removed and yet held in place by the resiliency of the tongue 10. The square 3 is divided by a pair of parallel lines 11 which extend centrally of both the rulers 4 and 5. On the outside of the square

there are provided a number of indications for marking off construction lines for a shirt waist body.

As shown in Figure 1, the sheet of paper 1 is provided with what may be termed vertical construction lines 12, 13, 14, 15 and 16 and horizontal construction lines 17 and 18. These lines are preferably made red while auxiliary vertical construction lines 19, 20, 21 and 22 are black. In addition, horizontal lines 23 and 24 are made black as well as a special diagonal line 25. These lines are provided in order to guide the person drawing the pattern so that the proper lines of the pattern may be secured. The square 3 is provided with graduations indicating inches and fractions thereof so that proper distances may be covered when desired and in addition, there are provided on the outside section of the rulers 4 and 5 various red stars 26, 26', 27, 28, 29, 30 and 31 which indicate where the various red lines are to be drawn. From these stars the red lines are drawn entirely across the sheet. On the outer half of the respective rulers 4 and 5 are also provided black stars 32, 33, 34, 35, 36 and 37. These black stars indicate where the various black lines are to be ruled. The black lines from the ruler 4 are to extend downwardly to the line 18 while the lines 23 and 24 extend different distances inwardly. Line 23 is intended to extend three-fourths of an inch inwardly from the red line 16 while line 24 also extends three-fourths of an inch inwardly from the red line 15. By positioning these lines as set forth, the dart lines 37 may be properly located and also certain other lines may be located by reason of point 38. When the various lines have been all provided, the point 39 is secured by an actual measurement of the rear from the neck down to the waistline and also the point 40 is secured by an actual measurement from the neck down to the waistline in front. These two points having been secured, line 25 may be drawn so as to connect these points and thereby give the waistline of the garment.

On the sections inside of the double lines 11 are provided red stars 41, 42, 43, 44, 45, 46, 47 and 48. These stars are to provide for proper construction lines for a sleeve. Associated with these markings are black stars 49 and 50 for constructing vertical black lines which extend down to the line 51, said line 51 extending horizontally

from the star or designation 48. With these construction lines, the dressmaker may readily draw the pattern lines. The various construction lines illustrated in Figures 5 1 and 4 are for a certain size garment but if a larger or smaller garment was necessary, the same lines would be provided and an allowance would be made for the different size dresses. In most instances, a quarter 10 of an inch would be allowed at four seams in each half of a garment for the difference in one size. By allowing a short distance like this on each line, the aggregate allowance will equal two inches for the 15 entire garment.

After a person has once learned how to use the square to make the construction lines and learned the rules of sketching the pattern lines, a pattern may be quickly made by using 20 the various arbitrary signs found on the square. In order to find the distance in special cases like the point 38 and the end of line 24, any part of the square may be used to measure this distance. Also the other points 25 of the pattern lines may be readily located by the usual inch graduations on the square. The square may be taken apart and used as independent rulers for measuring purposes if desired but when used to properly position 30 the construction lines, it is preferably arranged as a square and held in a given position until the desired lines have been provided.

What I claim is:

35 1. A square for designing garment patterns, comprising a right angled body having each of its members provided with a central division line and graduated in inches

on each side of said line throughout its length, one member having along its outer 40 edge two sets of differently colored marks, one set of marks being between the other set and spaced different distances from the edge, and the other member having on its outer edge two sets of differently colored 45 marks, one set of marks being beyond the first set and spaced a less distance apart than the first set, whereby vertical and horizontal construction lines of a garment may be produced, each member of the square being provided on its inner edge with colored marks and one member being provided with two marks of a different color and located between two of the first named marks, whereby the vertical and horizontal construction lines of a sleeve may be produced. 50

2. A square for designing garment patterns, comprising a right angled body having each of its members provided with a central division line and graduated in inches 60 on each side of the said line throughout the length of the member, one member having along its outer edge two sets of differently colored marks, for producing vertical construction lines of a garment body, one set 65 of marks being between the other set and located at different distances from the edge, and the other member having on its outer edge two sets of differently colored marks 70 for producing horizontal construction lines of a garment body, one set of marks being beyond the first set and spaced a less distance apart than the first set.

ANTOINETTE ZINGALI.
